UNITED STATES PATENT OFFICE:

BORIS NIKOLAEVITCH SOKOLOFF, OF RIDGEFIELD PARK, NEW JERSEY, ASSIGNEE TO
T. A. GILLESPIE COMPANY, A CORPORATION OF DELAWARE.

DETONATING-FUSE.

1,221,102.

Specification of Letters Patent.

Patented Apr. 3, 1917.

Application filed September 18, 1916. Serial No. 120,771.

To all whom it may concern:

Be it known that I, BORIS NIKOLAEVITCH SOKOLOFF, a subject of the Czar of Russia, residing at Ridgefield Park, in the county 5 of Bergen and State of New Jersey, have invented certain new and useful Improvements in Detonating-Fuses, of which the following is a specification, reference being had to the drawing accompanying and forming 10 part of the same.

My invention relates to detonating fuses in which the percussion rod or striker is held in position by a flat clip resting on a sleeve, until the clip is flattened by an impact which throws the sleeve past the clip and until a second impact in the opposite direction throws the percussion rod forward. An explosive cap is attached to the percussion rod so that when the latter is thrown 20 forward by the second impact a stationary needle which is inside of the axial bore of the percussion rod is struck by the cap and explodes the latter. The explosion of the cap causes explosion of the detonator inside 25 the body of the fuse. The objects of my invention are to provide a needle or firing pin which is separate from the "percussion mechanism" (described hereinafter) so that the needle or firing pin need not be placed 30 in position until the shell is to be used, thereby making the fuse safer; to provide a guide for the firing pin, thereby restricting lateral movement of the needle and preventing 35 breakage of the needle due to such lateral movement; to eliminate the necessity of attaching the needle-head to the collar of the percussion rod; and to eliminate the necessity of cutting a longitudinal slot in the percussion rod.

40 In the accompanying drawing,

Figure 1 is a longitudinal section of a complete detonating fuse embodying my invention.

Fig. 2 is a longitudinal section of the percussion rod.

Fig. 3 is a side view of the percussion rod collar.

Fig. 4 is a side view of the needle or firing pin.

50 The body of the "fuse" is designated by *a*, and is of elongated tubular form, threaded at the top, or outer end, for securing it in the end of the shell, not shown. The detonator *b*, inside the body *a*, is in the form 55 of a cylindrical chamber of annular cross

section, thus providing a longitudinal bore or passage through it. The plugs *c* and *d* are screwed into the bottom of the body *a* to close the latter and hold the detonator *b* in place.

60 The percussion mechanism is assembled separately, and comprises the percussion rod *l* having an axial bore or passage *r* through it; a collar *m*, slipped into the percussion rod up to the shoulder *l'* and having a circumferential groove *t*; a sleeve *h*, suitably secured to the collar *m*, as by crimping the end of the sleeve into the said groove, the sleeve inclosing the upper end of the percussion rod; the safety clip *k* fitted on the 70 upper end of the percussion rod; a sleeve *g* lying between the clip *k* and the overhanging upper edge of the outer sleeve *h*, thus serving to normally prevent outward movement of the percussion rod and itself prevented from inward movement by the clip *k*; and a spring *f* bearing on the upper or outer end of the percussion rod and on the overhanging upper edge of the sleeve *h* to resist upward, or outward, movement of the 75 rod, but permitting such movement at the proper time, as explained below. On the lower, or inner, end of the tubular percussion rod is an explosive cap *o*, secured in place by crimping and by a ring *p*.

80 The percussion mechanism described is inserted into the body *a* from above, (the screw-plug or nosepiece *e* being of course removed), so that the cap *o* lies below the detonator *b*. The firing pin *s* is now slipped 85 into the bore of the percussion rod, its head resting on top of the percussion mechanism and its pointed lower end positioned well within the detonator *b*. The nosepiece *e* is then replaced, and the fuse is then complete, ready for action.

90 When the gun into which the shell is loaded is discharged, the inertia of sleeve *g* causes it to lag behind the rest of the fuse. In effect, this amounts to driving the sleeve 95 backward. The clip *k* is flattened and the lower end of the sleeve *g* is brought below the clip, thereby leaving the percussion rod *l* free to move forward, except for the resistance offered by the helical spring *f*. When the shell strikes the ground or other object the momentum of the percussion rod *l* throws the same forward against the tension of the spring *f*, thereby bringing the explosive cap *o* against the pointed inner end 100 105 110

of the firing pin *s*. The cap is thus exploded, thereby exploding the detonator *b*, which in turn explodes the charge in the shell, not shown. It will be observed that 5 the cap *o* strikes the end of the firing pin at a point inside the detonator, thereby causing instant and certain explosion of the latter.

If desired, the firing pin *s* can be omitted, 10 thus making the shell entirely safe during handling and shipment. Then the pin can be placed in position after, or just before, the shell is sent to the firing line.

What I claim is:

- 15 1. In an impact fuse for explosive shells, in combination, a chamber containing a detonating charge, a longitudinally movable tubular percussion rod, having imperforate walls and having its body portion extending through the detonating chamber, an explosive cap attached to one end of the percussion rod and normally positioned outside of the detonating chamber, and a firing pin, removably attached to the striking end of 25 the fuse and extending into the bore of said

percussion rod, the inner or rearward end of the firing pin being inside the detonating chamber.

2. In an impact fuse for explosive shells, in combination, a detonating chamber containing a detonating charge, a longitudinally movable tubular percussion rod extending rearwardly through the chamber and having imperforate walls, means serving to normally hold the percussion rod against forward movement but releasable by the impact of starting the shell in the gun from which it is fired to permit such movement under the influence of the striking impact of the shell, an explosive cap carried on the inner 30 or rearward end of the percussion rod in rear of the detonating chamber, and a firing pin removably connected to the forward end of the fuse, extending rearwardly into the tubular percussion rod and terminating inside the detonating chamber.

BORIS NIKOLAEVITCH SOKOLOFF.
